DESIGN FOR A MOP WRINGER

Frank M. Fritsch and Lawrence B. Fritsch,
Hamilton, Ohio

Application September 9, 1941, Serial No. 103,260

Term of patent 14 years

To all whom it may concern:

Be it known that we, Frank M. Fritsch and Lawrence B. Fritsch, citizens of the United States of America, residing at Hamilton, in the county of Butler, State of Ohio, have invented a new, original, and ornamental Design for a Mop Wringer, of which the following is a specification, reference being had to the accompanying drawing, forming a part thereof.

The figure is a perspective view of the mop wringer, showing our new design.

The opposite side of the article is substantially like the side shown on the drawing.

The characterizing features of the design reside in a mop wringer composed of the elements disclosed, said elements having the configurations and arrangement specifically as shown.

We claim:

The ornamental design for a mop wringer, as shown and described.
